ADOLF P. C. URBIN, JR., OF MOUNT VERNON, NEW YORK.

LIQUID-FOUNTAIN.

1,268,646.

Specification of Letters Patent.

Patented June 4, 1918.

Application filed July 9, 1917. Serial No. 179,443.

To all whom it may concern:

Be it known that I, ADOLF P. C. URBIN, Jr., a subject of the Emperor of Germany, residing at Mount Vernon, in the county of 5 Westchester and State of New York, have invented new and useful Improvements in Liquid-Fountains, of which the following is a specification.

This invention relates to dispensing beverages, and more especially to beer apparatus in which the liquid is under gas pressure supplied to a separate chamber; and the object of the same is to produce a portable device such as a demijohn or portable dispenser capable of being refilled and re-used when the initial supply is exhausted, but possessing details of structure whereby its interior may be reached as for cleansing or repair.

20 Details are found in the following specification, reference being had to the accompanying drawings wherein:—

Figure 1 is a side elevation of this demijohn complete, showing the liquid outlet pipe carried to quite a height above its cover so that the glass or mug may be filled with beer drawn from the faucet as illustrated.

Fig. 2 is an enlarged vertical section through the dispenser complete.

30 Fig. 3 is a yet further enlarged section showing the gas valve and the pressure regulator therefor.

Fig. 4 is an enlarged sectional detail of the faucet.

35 The container proper is made in two parts, the first being a tank 1 of considerable size adapted to contain the liquid, and the second a hollow cover 2 divided by an upright partition 3 into a gas chamber 4 and a regulator chamber 5. These principal parts may have flanges with mating grooves and projections 7 and packing 8 between them, and the flanges may be connected by bolts 9 or other fastening means so that the bottom 40 plate 10 of the cover closes the open top of the tank 1 airtight.

The liquid outlet pipe 11 runs from a point near the bottom of the tank upward through the bottom plate 10 of the cover, upward through one of its chambers and also through the top plate 12 of said cover, above which it has a coupling 13. To the latter is attached the stem 14 of the faucet best seen in Fig. 4, which stem has a companion 55 coupling member 15 for this purpose, and when the same is removed from the coupling

13 and borne aside, the liquid contents of the tank may be supplied through the pipe 11. The faucet proper has a nozzle 16 above which it is enlarged as at 17 to contain a valve disk 18 pressed closed by a spring 19, and a pivoted handle or thumbpiece 20 is provided for overcoming the pressure of said spring and opening the valve to permit the liquid to flow out the nozzle. If such liquid is beer, it will be obvious that the foam will rise within the enlargement 17 and the liquid without the foam will flow out the nozzle, but after the valve is permitted to close the foam within the enlargement or chamber 17 will itself run out the nozzle in a manner which will be clear. However, I may employ any appropriate form of faucet.

Within the gas chamber 4 is located the 75 gas valve as seen in Fig. 3. Its casing 21 is preferably carried by the partition 3 and has its inlet at the bottom, whereas the outlet pipe leads from the top laterally and thence downward as at 22 and through the 80 bottom plate 10 of the cover and into the upper portion of the tank 1 above the liquid which of course settles in the bottom of the same; therefore when this valve is open, gas flows from the chamber 4 into the tank 1. 85 The turning plug 23 whose stem 24 leads through the partition and carries a lever 25, and from said stem also a rod 26 leads upward through suitable packing in the top plate 12, and has a handle 27 above said 90 plate so that the valve can be manually controlled from the exterior. When it is open it is obvious that gas will flow from the chamber 4 into the tank: when it is closed, or rather when the handle 27 is left free, the 95 action of this valve 23 is controlled by the regulator described below. Through the top plate 12 passes a gas feed pipe 28 having a nipple 29 at its exposed end and a check valve 30 on its interior, and when the nipple is connected with a suitable source of gas supply (or compressed air) such fluid agent may be pumped into or admitted to the chamber 4 for subsequent use in a manner yet to be explained. In its entry into the 105 chamber it passes the check valve 30, but this valve obviously prevents its escape.

The automatic regulator is best seen in detail in Fig. 3. This comprises a cup or cylinder 31 whose lower end opens through 110 the bottom plate 10 of the cover and whose upper portion contains a bridge 32, a pis-

ton 33 within the body of the cup, an expansive spring 34 between this piston and the bridge, and a piston rod 35 rising through this spring and bridge and out the top of the cup, above which it is pivotally connected at 36 with the free end of the lever 25. A nut 37 on this rod controls the action of the regulator, and may be adjusted to cause it to act earlier or later as described.

10 Let us assume that this dispenser is to be used for containing and delivering beer. Before the stem of the faucet is applied at the point 13, the beverage is supplied through the pipe 11 and enters the tank 1 under considerable pressure and carrying its gas with it. This gas is trapped within this tank above the level of the beer, and by manipulating the handle 27 the valve 23 may be opened to permit the gas to flow into the chamber 4. The tank having been charged, the faucet is re-connected at 13 and closed, and the handle 27 is released so that the valve 23 stands closed. Additional gas pressure can now be supplied to the chamber 4 through the nipple 29 and pipe 28, and the check valve 30 prevents its escape. The pressure within the tank above the liquid causes the latter to rise through the pipe 11, but its delivery from the faucet is prevented by the force of the spring 19 above the valve disk 18. When a glass of beer is to be drawn into a mug as indicated at M in Fig. 1, the operator moves the handle 20 and opens the valve disk 18, and the beer flows out the nozzle 16, followed later by the froth or foam in the manner suggested. This operation is repeated until finally the gas pressure within the tank 1 becomes depleted: 15 this permits the spring 34 to expand and the piston 33 to descend, and through its rod 35 and the lever 25 the valve 23 is opened and gas from the chamber 4 flows into the tank 1 above the liquid. As soon as the pressure has equalized itself, the piston 33 again rises and closes the valve 23; and thus the operation is kept up until the pressure within the chamber 4 has been depleted to such an extent that it will no longer force the liquid out the pipe 11. Now the pressure therein may be restored through the pipe 28 in a manner already suggested, and eventually almost the entire charge within the tank 1 can be delivered out the faucet. Obviously the operation can then be repeated without taking off the cover 2, although this is removable on occasions when the interior must be cleansed.

What is claimed as new is:—

- 60 1. In a liquid dispenser, the combination with the container divided into compartments constituting a tank for the liquid and a chamber for gas, a liquid outlet pipe leading from the bottom of said tank upward, 65 and a faucet whose stem has a coupling re-

movably attached to said pipe; of a gas valve in said chamber, the inlet end of its casing opening into the chamber and the outlet end thereof communicating with said tank, means for actuating said valve manually from the exterior of the dispenser, a regulator actuated by the pressure within said tank, and connections between the regulator and valve for opening the latter when the pressure falls.

75

2. In a liquid dispenser, the combination with the container divided into compartments constituting a tank for the liquid and a chamber for gas, a liquid outlet pipe leading from the bottom of said tank upward, 80 and a faucet whose stem has a coupling removably attached to said pipe; of a gas valve in said chamber, the inlet end of its casing opening into said chamber and the outlet end thereof communicating with said tank, means for actuating said valve manually from the exterior of the dispenser, a cup communicating with the upper portion of the tank, a piston therein, a spring for moving said piston downward against the 85 pressure within the tank, a piston rod rising from the piston through the upper end of the cup, a lever on the stem of said valve, and connections between said lever and rod, for the purpose set forth.

95

3. In a liquid dispenser, the combination with the container divided into compartments constituting a tank for the liquid and a chamber for gas, a liquid outlet pipe leading from the bottom of said tank upward, 100 and a faucet whose stem has a coupling removably attached to said pipe; of a gas valve in said chamber, the inlet end of its casing opening into the chamber and the outlet end thereof communicating with said tank, a gas feed pipe to said chamber, a check valve in said pipe, a cup communicating with the upper portion of the tank, a bridge across the interior of the cup, a piston movable in the cup beneath the bridge, 105 an expansive spring between the bridge and piston, a rod leading from the piston up through the spring and bridge, a lever on the stem of said valve, and connections between said lever and rod, for the purpose 110 set forth.

115

4. In a liquid dispenser, the combination with a container comprising an open-topped body constituting a tank, a hollow cover whose bottom plate closes the top of said tank, and means for connecting these elements in an air-tight manner, a liquid outlet pipe leading from a point near the bottom of said tank upward through the cover and having a coupling above the top plate 125 of the latter, and a faucet whose stem has a companion coupling; of a partition within the cover dividing it into a gas chamber and a regulator chamber, a gas valve whose casing is mounted on said partition with its in- 130

let end opening into the gas chamber and its outlet end communicating through the bottom plate of said cover with the interior of the tank, means for supplying gas under pressure to the gas chamber, the stem of said gas valve leading through said partition, a lever fast on said stem, and a pressure-
sure-actuated regulator within the regulator chamber communicating through the bottom plate of the cover with the interior of the tank and connected with the other end of said lever, for the purpose set forth.

In testimony whereof I affix my signature.

ADOLF P. C. URBIN, JR.
